UNITED STATES PATENT OFFICE

CHARLES J. TRAVERS, OF PORT WASHINGTON, WISCONSIN, ASSIGNOR TO GILSON MANUFACTURING CO., OF PORT WASHINGTON, WISCONSIN

SUPPORTING BASE

Application filed February 17, 1928. Serial No. 254,997.

This invention relates to supporting bases. Objects of this invention are to provide a novel form of supporting base which, although adapted for numerous other uses, is particularly adapted for supporting chairs, and which is so constructed that spreading of the legs cannot occur, but instead of which the legs are securely braced against spreading at both their upper and lower portions, and which is provided with a load receiving member which may be a spindle receiving member, and which is suitably carried by members secured to the legs in a rigid and permanent manner.

Embodiments of the invention are shown in the accompanying drawings in which:

Figure 1 is a view partly in section of the base.

Figure 2 is a sectional view on the line 2—2 of Figure 1.

Referring to the drawings it will be seen that the base is composed of a plurality of legs having straight portion 1 extending downwardly and slightly divergent and curved and extending outwardly to provide curved supporting bottom portions 2. A braced spider in the form of a metal plate 3 is positioned between the legs adjacent the bottom and is provided with a plurality of downwardly extending ears 4. These ears are curved to fit the curved bottom portions of the legs as shown in Figure 1 and are apertured and countersunk or depressed for the reception of screws or other fastening means 5, which extend therethrough and into the legs.

A second plate 6 is positioned between the legs as shown in Figure 1 and is provided with a plurality of downwardly extending apertured ears 7, these ears contacting with the inner surfaces of the legs and receiving bolts 8 whose heads are preferably inset on the outer side of the legs. These bolts or screws preferably are provided with washers 9 as shown in Figure 1. The plate 6 has its upper face disposed in a horizontal plane and is apertured for the reception of the lower end of the internally threaded spindle receiving sleeve 10. This sleeve is provided with an annular flange 11, the lower face of

which lies in a horizontal plane and rests upon the plate 6. The flange 11 is preferably disposed at a point adjacent the lower end of the sleeve 10. The plate 6, it will be seen, is a load carrying as well as a braced plate. 55 The upper portion of the spindle is provided with a substantially rectangular flange 12, which contacts with the underside of an apertured plate 13. This plate 13 rests upon the top of the legs 1, and is provided with a 60 plurality of depressed or countersunk apertured portions through which attaching screws 14 extend. Such screws project into the ends of the legs. The plate 13, it will be seen, securely holds the upper end of the 65 spindle receiving or load receiving sleeve 10. Any suitable means may be employed for preventing rotation of the spindle. It has been found convenient to make the flange 12 rectangular in contour, so that it bears 70 flatly against the inner sides of the upper portions of the legs.

If desired, foot rest supporting portions 15 may be secured to the legs and may extend outwardly therefrom.

It is to be distinctly understood that while this invention has been described as particularly directed to a chair base, it nevertheless is not to be limited to such use as obviously it can be used as any type of support for 80 furniture or other articles.

It will be seen that a very simple and attractive type of base has been provided, which is so constructed that the legs are rigidly held against spreading both at their upper 85 and lower portions.

It will be seen further that the device is simple to make and is of sturdy construction.

Although the invention has been described 90 in considerable detail, such description is intended as illustrative rather than limiting as the invention may be variously embodied and as the scope of such invention is to be determined as claimed.

I claim:

A supporting base comprising a plurality of legs having downwardly extending portions and outwardly curving lower supporting portions, a bracing plate having down- 100

turned and curved apertured ears contacting with the curved portions of said legs, securing means passing through the apertures in said ears and into said legs, a second plate spaced upwardly from said first plate, having a horizontally disposed upper face and laterally projecting ears arranged in a substantially vertical plane, bolts passing transversely through said ears and said second plate having an aperture therethrough, a third plate provided with an aperture and secured to the upper end of said legs and a spindle receiving sleeve projecting through the apertures in said second and third plates and having a flange formed with a horizontally disposed lower face resting upon said second plate, said flange having its outer edge spaced from the inner faces of the legs, said sleeve having an upper rectangular flange bearing against the under side of said third plate, and its side faces bearing against the inner faces of the upper ends of the opposed leg members.

In testimony that I claim the foregoing, I have hereunto set my hand at Fort Washington, in the county of Ozaukee, and State of Wisconsin.

CHARLES J. TRAVERS.
